ELECTRIC SWITCH

Winton G. Harlow, Upper Darby, Pa., assignor to
 General Electric Company, a corporation of
 New York

Application October 29, 1945, Serial No. 625,272

2 Claims. (Cl. 200—162)

1

My invention relates to improvements in electric switches and more particularly manually operable knife switches and especially fused knife switches.

Knife switches have, heretofore, involved the use of too much material, too much space on the panel or switch board as well as conducting and manual operating elements of involved construction or too many parts to provide a switch satisfactory from the standpoint of manufacture, reliability, flexibility of application and economy. Accordingly, an object of my invention is to provide an improved knife switch structure which is simple and economical to manufacture from relatively few parts and which is compact and readily adaptable for closely spaced fused switch panel mountings. Another object of my invention is to provide an improved finger-operated knife switch having a sturdy insulating finger-operable block handle close-coupled with relatively lightweight switch conducting parts conducting relatively high currents without serious heating. These and other objects of my invention will appear in more detail hereinafter.

In accordance with my invention, I provide a knife switch structure wherein a relatively light U-shaped blade member having a rectangular bight formed from a flat electric current conductor, is readily and rigidly secured to an insulating finger-operable channel block handle provided with a lengthwise extending rectangular mounting groove for registering nested engagement with the rectangular bight of the blade member so as to prevent movement thereof relatively to the handle and also to insure parallel alignment of the blade members in a multipole switch. Also in accordance with my invention, I provide a first round switch pivot stud terminating in a flat contact portion, a second round switch contact stud terminating in a cylindrical contact portion and having a motion limiting shoulder below the contact portion, and cooperating with these two studs, a U-shaped blade member for spanning the flat and the cylindrical contact portions and whose legs adjacent the rectangular bight are spaced apart sufficiently less than the diameter of the cylindrical contact portion of the second stud to insure relatively high contact pressure when the blade member and the second stud are in cooperative engagement. Further in accordance with my invention, the ends of the legs of the U-shaped blade member are inwardly offset to a spacing substantially equal to the thickness of

2

the flattened portion of the first stud to which the legs are pivotally clamped.

My invention will be better understood from the following description when considered in connection with the accompanying drawing, and its scope will be pointed out in the appended claims.

In the accompanying drawing, Fig. 1 is a side elevation, partly in section, of a double-pole fused finger-operable knife switch embodying my invention; Fig. 2 is a front elevation of the embodiment of my invention shown in Fig. 1; Fig. 3 is a sectional elevation on the line 3—3 of Fig. 1 showing the detailed construction of the combined switch pivot and fuse mounting stud but to a larger scale; Fig. 4 is a sectional elevation on the line 4—4 of Fig. 2 showing the insulating finger-operable block handle close coupled mounting on the rectangular bight of the switch blade but to a larger scale; and Fig. 5 illustrates a modification of a part of my invention.

For the purpose of illustrating my invention, I have shown in Figs. 1 and 2 a two-pole knife switch comprising a first row of round hinge studs 10, each terminating in a relatively thin flat portion 11 normal to the row, an opposite row of round contact studs 13 each terminating in a rounded contact portion 14 having its axis in opposing alignment with the flat portion 11 of the corresponding stud 10 in the first row and provided with a movable contact motion-limiting shoulder 15 below the contact portion 14, two spaced movable conductor elements 1, each of which comprises a flat electric current conductor bent approximately midway of its length to form a U-shaped blade member having a substantially flat rectangular bight 2 and legs 3. For actuating the blade members 1, I provide a close-coupled insulating finger-operable block handle 4 of suitable insulating material which has specially formed cooperating channels or grooves in each face thereof extending throughout the length of the block. Thus the handle has on its inner face a longitudinal groove 5 of a generally rectangular shape for registering nested engagement with the rectangular bights 2 of the blade members so as to reinforce and increase the rigidity of the flat rectangular bights as well as prevent movement thereof relatively to the handle and also to insure parallel alignment of the blade members in a multipole switch. The close-coupled block handle 4 may be of any suitable insulating material such as wood, molded compound and the like made up

in strips of uniform cross section so that lengths can be cut therefrom dependent on the number of poles in the switch. For convenience and safety in operating so as to insure a firm and well insulated finger grip on the handle, the handle strips are provided on the outer face with a deep longitudinal finger receiving and insulating depression or channel 6, the sides of which are corrugated at 7, and the sides of the strips are provided with longitudinal thumb grooves 8 which are also corrugated as shown. For clamping the rectangular bights 2 of the blade members in the registering rectangular groove 5 of the handle 4, suitable means such as screws 9 are provided.

For pivotally supporting the U-shaped blade members 1, each is provided with a hinge stud 10 which terminates in a flattened contact portion 11 that is of materially less thickness than the stud to provide parallel contact surfaces inwardly offset from opposite sides of said stud and provided with an axial opening for the reception of a hinge bolt 12. Also cooperating with each of the blade members 1 is a terminal or contact stud 13 which terminates in a cylindrical contact portion 14 and which has below the contact portion a motion limiting shoulder 15 for stopping the movement of the blade member in the switch closed position. For obtaining good contact alignment with more uniform contact pressure, the studs 10 and 13 are provided with suitable cylindrical contact surfaces. While the contact portion 14 of the stud 13 may take the form of a right circular cylinder, I have found less deterioration of the contact surfaces from arcing if the contact portion is in the form of an elliptical cylinder with the portions of lesser curvature presented to the legs 3 of the blade 1, as shown in Fig. 2. For the required contact area and mechanical rigidity at the hinge end, the thickness of the flat portion 11 of the hinge stud is materially less than the thickness of the contact portion 14 of the contact stud. The spacing of the legs 3 of the U-shaped blade member 1 is sufficiently less than the thickness of the cylindrical contact portion 14 to insure firm high pressure line contact between the legs 3 and the contact portion. In order to guide the legs 3 for the spreading action required during contact closure, the contact portion 14 is suitably shaped as by rounding the tip, shown more clearly in Fig. 2. Since the thickness of the flat contact portion 11 of the hinge stud 10 is materially less than the spacing of the legs 3 of the U-shaped member, the ends 16 thereof are inwardly offset to a spacing substantially equal to the thickness of the flat contact portion. For the desired contact action between the blades 3 and the flat contact portion, suitable resilient washers 17 are provided on the bolt 12. Thus with a given weight of conductive material, both the current conducting and heat dissipating capacities thereof can be utilized most effectively since the required mechanical strength is provided by the rectangular bight of the relatively light U-shaped blade 1 spanning the round pivot stud 10 with a flattened end and the cylindrical contact stud 13 so that relatively high currents can be conducted without serious overheating. The relatively wide spacing of the legs 3 at the bight with the inward offset only at the pivot ends thereof facilitates circulation of the air therebetween to dissipate heat.

In order to insure more firm contact between the blades 3 and the contact portion 14 of the contact stud 13, especially under shock conditions, the blades 3 may be resiliently intercon-

nected adjacent the stud by suitable means such as a bolt 18 passing through spring washers 19 in engagement with the blades. The contact stud 13 has a threaded portion 20 which projects through an opening in a switch base 21 of suitable insulating material, movement of the stud through the opening being limited by a shoulder 22 below which are deformed lugs 23 for preventing rotation of the stud relatively to the base when a clamping nut 24 and washer 25 are tightened to the holding position.

In order that switches embodying my invention may be used with fuses having blade type terminals, the stud 10 is illustrated as a combination fuse clip and switch stud, all as disclosed and claimed in my copending application for Letters Patent of the United States, Serial No. 597,884, filed June 6, 1945, which subsequently issued as Patent 2,458,511, on January 11, 1949. Thus there is provided a clip member 26 for holding the blade type terminal 27 of a fuse 28 in relatively high pressure substantial line-contact against the cylindrical surface of the stud 10. The clip member 26 is resilient and of relatively low electric current conductivity in comparison with the conductivity of the stud 10. The clip member 26 is provided with a relatively small contact surface 26' opposed to the surface of the stud 10 for engaging the fuse terminal 27 in relatively high pressure contact having a minimum of area and approximating point-contact. For easy insertion of the fuse terminal 27, the contact surface 26' is convex and is so positioned as to localize the pressure approximately midway of the line of contact between the surface of the stud and the fuse terminal.

For mounting the stud 10 and the clip member 26 on the base 21, the clip member is secured against a shoulder 29 of the stud by a shouldered plug 30 which is threaded into the bottom of the stud, as shown in Figs. 1 and 3, and the stud 10 and the clip member 26 are interlocked to prevent relative movement by providing the shoulder 29 of the stud 10 with a depressed surface for the reception of a raised portion 31 on the clip member. The free end of the plug 30 projects into a hole in the base 21 and as shown is threaded for a fastening screw 32 under the head of which are a lock washer 33 and a bearing washer 34. For mounting the other end of the fuse, I provide a fuse clip 35 which is essentially similar in construction to the combination fuse clip and stud 10 except that the cylindrical portion does not include a flat surface for hinging the switch blade. Also, the clip 35 is provided with a threaded portion 36 which projects through an opening in the base 21 and is held in position on the base by a nut 37 over a washer 38. The stud 36 is thus suitable for terminal connections.

When a double-throw switch is desired, two contact studs 13 are provided respectively positioned on opposite sides of the hinge stud 10 as will be obvious to those skilled in the art. If a double-throw switch is to be used for individually controlling two different circuits, each of which is to be fused separately, then as shown in Fig. 5 the contact stud 13 for each throw is provided with a fuse clip member 26 for receiving the tongue type terminal 27 of a fuse 28 between the cylindrical surface of the stud and the contact surface 26' of the clip.

While I have shown and described my invention in considerable detail, I do not desire to be limited to the exact arrangement shown, but seek to cover in the appended claims all those modifica-

tions that fall within the true spirit and scope of my invention.

What I claim as new and desire to secure by Letters Patent of the United States is:

1. A multipole finger-operable knife switch having in combination, a row of round contact studs, an opposite row of round hinge studs, each terminating in a flat portion having a U-shaped blade member pivotally mounted thereon and comprising a flat conductor bent approximately midway of its length to form a substantially flat rectangular bight for sustaining high contact pressure upon engagement of a corresponding round contact stud between the legs thereof adjacent the bight, a block handle of insulating material having a finger receiving and insulating channel in one face thereof extending throughout the length of the handle and a parallel rectangular groove in the opposite face thereof for registering nested engagement with the rectangular bights of the U-shaped blade members with the legs thereof extending transverse the groove, and means for clamping the bights of the U-shaped blade members in said groove to maintain the blades in a row and in longitudinal alignment with the channel in the handle.

2. A multipole finger-operable knife switch having in combination, a first row of round hinge studs, each terminating in a relatively thin flat portion normal to the row, an opposite row of round contact studs, each terminating in a rounded contact portion having its axis in opposing alignment with the flat portion of the corresponding stud in the first row and provided with a motion-limiting shoulder below the contact portion, a movable row of blades, each comprising a flat conductor bent approximately midway of its length to form a U-shaped blade member having a substantially flat rectangular bight for sus-

taining high contact pressure upon engaging the rounded contact surface of a corresponding stud between the legs thereof adjacent the bight up to the limit of the shoulder and the ends of said legs being inwardly offset for straddling engagement with the relatively thin flat portion of the corresponding stud in the first row, means for pivotally clamping the offset ends of each blade to the flat portion straddled thereby to maintain the blade in pivotal conducting relation therewith, a block handle of insulating material having a finger receiving and insulating longitudinal channel in one face thereof extending throughout the length of the block and a parallel rectangular groove in the opposite face thereof for registering nested engagement with the rectangular bights of said U-shaped members with the legs thereof transverse the groove, and means for clamping the bight of each U-shaped blade member in said groove to maintain the blades in fixed alignment with the channel in the handle during pivotal movement of the row of blades.
